UNITED STATES PATENT OFFICE

101,293

DESIGN FOR A FINGER RING

Milton W. Stern, New York, N. Y.

Application August 8, 1936, Serial No. 64,310

Term of patent 3½ years

To all whom it may concern:

Be it known that Milton W. Stern, a citizen of the United States of America, residing at New York, in the county of New York and State of New York, has invented a new, original, and ornamental Design for a Finger Ring, of which the following is a specification; reference being had to the accompanying drawing, forming part thereof:

Fig. 1 is a perspective view of a finger ring showing my new design, and

Fig. 2 is a side elevation of the same.

I claim:

The ornamental design for a finger ring as shown.

In testimony whereof I affix my signature.

MILTON W. STERN.
